(57) CLAIM

The ornamental design for a pair of motorcycle fender struts, as shown and described.

DESCRIPTION

FIG. 1 is an isometric view of one of the pair of motorcycle fender struts, for the right side of a motorcycle, showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and,

FIG. 8 is an isometric view of one of the pair of motorcycle fender struts, for the left side of a motorcycle, which is a mirror image of the motorcycle fender strut of FIGS. 1-7.
